Walter W. Standard, of Buffalo, N.Y.

Assignor to

S. J. Jewett and F. H. Root
Letters Patent No. 1317 dated Sept. 30, 1860.

The schedule referred to in these Letters Patent and making part of the same.

To all whom it may concern:

Be it known that I, Walter W. Standard, of the City of Buffalo,
County of Erie, and State of New York, assignor to Sherman J. Jewett & Francis H. Root, of Buffalo,
aforesaid, have invented or produced a certain new and original design for Cooking
Stoves, and I do hereby declare that the following is a full, clear and exact description
thereof, reference being had to the accompanying drawings (photographic) and the
letters of reference marked thereon—

Fig. I. Represents the front plate of the stove.

Fig. II. Represents one of the side plates of the stove.

Fig. III. Represents one of the end plates of the elevated oven.

Fig. IV. Represents one of the side plates of the elevated oven.

In Fig. I. a, a, are two sliding doors with raised panels surround-
ed by an "ogee" and bead moulding. The panels have each an embossed or-
nament composed of reversed scrolls (b) expanding corrugations (c) and carved work (d)
arranged as represented. The panels of the jambs on either side of the sliding doors have
an embossed ornament composed of the central ovate bead (e) radiating corrugations (f)

terminating in an ovate ring having adhering leaves (q) symmetrically arranged at the ends and sides.

In Fig. II h. is the door which opens into the fire chamber. It is surrounded by plain round and concave, and bead mouldings as represented.

Near the lower edge of the panel is an ovate bead or emboss (i), from which the corrugations (j) radiate or expand towards the top and sides, terminating in the embossed scrolls (k) as represented with reversed scrolls terminating in beads at the lower corners.

The edge of the plate is surrounded by a plain moulding as represented.

In Fig. III (l) is the door which opens into the oven. It is surrounded by plain round and concave mouldings as represented, and its upper corners are rounded. It has an ovate shield like boss (m) a short distance below the centre, from which expand or radiate the embossed corrugations (n) longer towards the top and sides, than towards the bottom as represented. They terminate at the top in the arched moulding (o), and at the sides in the embossed leaves and scrolls as represented, at the bottom are the external embossed scrolls (p), curved in opposite directions, and their contiguous ends terminating in beads as represented.

The opposite end plate is the same, in all respects as the one just described, except that the door is a stationary panel.

In Fig. IV. the plate is ornamented by a large star like figure, with four points pointing towards the four edges of the plate, and surrounded by the denticated moulding (q). At the center of the plate and star is a corrugated oval emboss (r) with a small central bead (s) from which the corrugations radiate. Star points (t) extend from this central corrugated emboss (r) to the points of the large star, and have denticated ridges through their centers. (u) are leaf like ornaments arranged between the star points, their stems pointing to the central bead. (v) are embossed scroll ornaments with adhering leaves arranged at the corners of the plate as represented.

What I claim and desire to secure by letters patent, is the ornamental design for a Cooking Stove herein described and represented in the accompanying photographic drawings.
